UNITED STATES PATENT OFFICE.

PETER VANDERNOTH, OF NEW YORK, N. Y.

SELF-OPENING LID FOR CABINETS, &c.

SPECIFICATION forming part of Letters Patent No. 326,810, dated September 22, 1885.

Application filed July 29, 1885. (No model.)

To all whom it may concern:

Be it known that I, PETER VANDERNOTH, of the city, county, and State of New York, have invented a new and useful Improvement 5 in Self-Opening Lids for Inclosed Wash-Stands, Cabinets, Pianos, &c.; and I do hereby declare that the following is a full and exact description thereof, reference being had to the accompanying drawings, and to the letters of 10 reference marked thereon, making a part of this specification.

My invention relates to the lids or hinged covers of cabinets, ice-boxes, wash-stands, pianos, and other pieces of furniture, and has 15 for its object an automatic opening of the lid when required.

In the accompanying drawings, Figure 1 is a view in perspective of a cabinet wash stand having my invention applied thereto, and Fig. 2 is a central vertical section thereof with the inner plate or lining of the casing at the end of the wash-stand removed to disclose the weight and spring therein.

A represents an inclosed wash-stand (or 25 other piece of furniture) provided with a hinged lid, B, to cover and close the top thereof. At each end of the lid and to its inner face segmental side pieces, C C, are secured to project therefrom in position to drop immediately within the ends of the stand when the 30 lid is closed. The lower edge of each segmental plate projects at a right angle with the lid, so that when the lid is closed this edge will rest against the inner face of the back of 35 the stand.

Friction rollers or pulleys D are mounted to rotate upon stud-pins projecting within the stand at its inner front corners. Each roller is thus immediately in front of the end of the 40 lower edge of each segmental side plate, C, when the lid is raised.

A cord, E, carrying a weight, F, is led over each pulley and attached to the end of the lower edge of the segmental side plate, as illustrated in Fig. 2, the weight being made to move up and down in the corner of the stand as the lid is lowered or raised. The gravity of these weights tends automatically to throw up the lid by reason of the tension produced thereby upon the cords E E, operating to draw upward and outward the ends of the side plates, 50 C C, of the lid to which they are attached.

When the lid is closed, it is kept in position and the elevated weights are upheld by means of a rotating or other suitable spring-catch, 55 G, fitted to the front of the case to engage a catch-plate, G', on the lid.

So soon as by a movement of the catch G the lid is set free, it will, under the influence of the weights F, automatically fly open. To 60 obtain a quicker movement of the lid in opening when it is liberated from its catch, I insert a flat spring, H, at the back of the case on the inner side in position to be engaged and compressed by the inner or lower edge of each 65 side plate, C, when the lid is closed. (See dotted lines, Fig. 2.) These springs are thus made to come into play to assist in overcoming the dead-weight or inertia of the lid when its catch is released, the movement of the lid 70 being completed by means of the weights, as described.

The weights and springs are concealed within the narrow compartments, partitioned off by inner side plates or boards, L, (see Fig. 1,) 75 at each end of the case.

In the use of my invention, when it is desired to open the cabinet, a simple movement of the catch G, by releasing the lid, will permit the springs H and weights F to come into play. 80 The springs will at once, in connection with the weights, operate to raise the closed lid, and the weights, which at the start work at a disadvantage from want of leverage upon the side plates of the lid, will, when the lid has 85 started, complete its movement and throw it wide open. The cords E E, as the lid is closed, are held in proper position upon the curved edge of each side plate, C, of the lid by means of a groove cut in the face of said edge to partially inclose the cord.

It is evident that an arm or skeleton bracket projecting at right angles with the lid from its inner side may be substituted for the solid segmental side plates, C C, constructed as 95 shown and described, for the purpose of engaging the cords E E; but the segmental side plates are preferred, as they serve the double purpose of neatly inclosing the top of the stand when the lid is open.

In applying my invention to piano-lids, if the lid is to be opened very wide the weights may be made to pass down within the front legs, made hollow for the purpose. Ordinarily,

however, it is not required to raise the lid far, and sufficient room will be found within the case for the weights.

I claim as my invention—

- 5 1. The combination, with a hinged lid, B, of an inclosed stand or case, and with an arm or lateral plate, C, projecting therefrom, of a weight, F, and cord E, attached to the outer end of said arm or plate and led over a pulley, D, rotating on a stud secured to the inner side of the stand or case, and a catch, G, engaging said lid when closed, substantially in the manner and for the purpose herein set forth.
- 10 2. The combination, with the hinged lid of an inclosed stand or case, and with an arm or

lateral plate, C, projecting therefrom, a cord, E, attached to its outer end, led over a pulley, D, and carrying a weight, F, and a catch, G, engaging the lid, of a spring, H, fixed on the inner side of the stand or case to be compressed 20 by the arm or plate C when the lid is closed, substantially in the manner and for the purpose herein set forth.

In testimony whereof I have signed my name to this specification in the presence of 25 two subscribing witnesses.

PETER VANDERNOOTH.
